Primary Examiner—James Gandy*Assistant Examiner*—Stacia Sinuik*Attorney, Agent, or Firm*—Evenson, McKeown, Edwards & Lenahan, P.L.L.C.[57] **CLAIM**

The ornamental design for a front face of a wheel, as shown and described.

DESCRIPTION

FIG. 1 is a side view of a front face of a wheel according to our novel design; and,

FIG. 2 is a perspective view of a front face of a wheel according to our novel design.

The broken lines illustrate environmental structure only and form no part of the claimed design.
